MAURICE B. COOKE, OF PLAINFIELD, NEW JERSEY, ASSIGNOR TO THE ATLANTIC
REFINING COMPANY, OF PHILADELPHIA, PENNSYLVANIA, A CORPORATION OF
PENNSYLVANIA

PROCESS AND APPARATUS FOR FRACTIONAL DISTILLATION

Application filed August 27, 1926. Serial No. 131,914.

My invention resides in a method of and apparatus for fractionating vapors, involving their passage in contact with reflux liquid, with withdrawal of liquid from the fractionating system and return of at least a portion thereof, after cooling, to the fractionating system.

More particularly my invention relates to improvements in a continuous process for making lubricating oil distillate, which is of a higher quality than that made by other processes, particularly in that the boiling range of the distillate is limited to predetermined temperatures whereby a more satisfactory lubricating distillate may be obtained from crudes of a different character, namely, asphaltic or paraffine base products.

The invention has further to do with a process for making pressable lubricating oil distillate, and comprises a method wherein crude oil or other lubricating oil bearing liquids are withdrawn from one or more trays of a conventional bubble tower fractionating device continuously in the liquid phase.

The use of other forms of fractionating towers common in modern refineries are unsuitable for preparing a pressable lubricating oil distillate carrying paraffin wax, for the reason that there is insufficient fractionation or separation of deleterious substances existing in the crude oil or other lubricating oil bearing liquids. In other distillation systems lubricating oil distillate or wax distillate is obtained by fractionably separating the

several constituents of crude oil in the vapor phase, the vapors of the products desired are removed from the respective stages of the fractionating device and condensed. In the present invention the lubricating oil distillate is removed from the fractionating tower in the liquid phase and comparatively free from heavy coloring material as well as colloidal carbon and asphalt.

A further object of the invention is to produce in one distilling operation a lubricating oil distillate having a minimum boiling point range, a distillate which is comparatively free from coloring material, asphalt colloidal carbon and other deleterious substances.

In one distilling operation a lubricating

oil distillate is produced carrying paraffine wax having such physical and chemical characteristics that the wax may be removed by conventional pressing operation. As a matter of fact lubricating oil distillate as it is produced at the present time has such physical and chemical characteristics that the wax cannot be removed by ordinary chilling, and separation by present methods. As ordinarily made the lubricating oil distillate is removed from the fractionating device in the vapor phase and vacuum, steam or fixed gas is employed in order that the viscosity of the lubricating stock will not be destroyed by excess heat necessary to vaporize the oil and wax. Consequently lubricating oil distillate so made is of such physical structure that the wax when chilled with the oil is not in condition that all of the lubricating oil cut can be freed of wax by pressing methods. Therefore, part of the lubricating oil distillate is placed usually in a cylindrical still and subjected to heat without the use of steam, or with a very little steam, and in this way the wax and oil are cracked and the physical nature of the wax particles changed to the extent that when the oil is chilled the wax will be in such physical condition that it can be removed by pressing.

The figure is a diagrammatic side elevational view of an apparatus in which the process may be practiced with parts in section and parts broken away.

In the drawings at 1 is shown a furnace in which is mounted a pipestill 2. The discharge end of the still is connected by means of a line 3 to a bubble tower 4. 5, 6 and 7 are heat exchangers; 8 is a cooler and 9 a pump.

Referring now to the method of operation. Crude oil is supplied through the line 10 from any convenient source of supply, and is pumped through the heat exchanger 5 where it acquires heat from the vapors coursing in radiating contact with it through the heat exchanger. On being discharged from the exchanger the oil is directed through a line 11 through a second heat exchanger 6, where it is brought in heat exchange relation with the lubricating oil distillates withdrawn from

100

the bubble tower through the pipes 12 and 13.

After this additional heating in the second exchanger 6 the charge passes through a final heat exchanger 7, through which the products withdrawn from the bottom of the bubble tower through the line 14 are circulated.

From the heat exchanger 7 the oil passes through a line 15 to the pipestill 2 where it is raised to a temperature which will produce the desired degree of evaporation. The oil from the pipestill is directed to the line 3 and is allowed to expand in the evaporation section, or lower portion of the bubble tower 4. Here the light volatile portions of the crude evaporate and percolate through successive pools of oil supported by the bubble trays 16. The percolation of the vapors through these pools of oil is produced by capped risers 17.

The successive pools of oil are of decreasing temperature toward the top of the tower so that the vapors which pass off through the line 18 are only the lighter cuts which after passing through the heat exchanger are directed to a final condenser not shown through the pipe 19. Any condensate separated out in the heat exchanger is returned through the reflux line 20 to the top of the bubble tower. Between the bubble trays are positioned layers of broken up material, or screens 21, which serve as mist extractors, and prevent the passage of entrained material from one pool to the next pool above. The heavier portions of the oil vapors are liquefied by coming in contact with the reflux liquid carried on the trays. The unvaporized portions of crude oil are allowed to collect in the bottom of the tower 4, and are continuously withdrawn in regulated quantities, and used as fuel oil or for any desired purpose. The lubricating oil distillate or wax distillate is collected on the trays in the upper part of the tower and may be withdrawn continuously through the pipes 12 and 13. The distillate withdrawn through the pipe 13 will be heavier in specific gravity than that withdrawn from the pipe 12, and so in each of the trays above distillate will be of decreasing gravity.

In order to produce a lubricating oil distillate having a very narrow range of boiling points it has been found that by returning oil withdrawn from the tower through the line 13, and passing the same through the exchanger 6, and cooler 8, and returning this distillate by charging it through a pump 9 and line 22, back to the tower just above the tray's from which the lubricating oil distillate is withdrawn, a much more desirable distillate is produced. The cooler 8 may be either water or air cooled. Cuts or fractions withdrawn from the lines 12 and 13 will be in the liquid phase and will have had the heavy impurity, such as asphaltum, colloidal carbon and light impurities such as gas, oil, kerosene and naphtha fractions, separated

therefrom by fractional condensation and vaporization, substantially as described.

It is also clear that cuts or fractions withdrawn from one or more bubble trays will have a smaller number of degrees boiling range (initial boiling point to end boiling point), and will consequently have a minimum boiling range for a given viscosity. This is an important advantage in the present invention, for it has been found that the quality of a lubricating oil depends on two characteristics:

First—If oils having the same viscosity are tested for lubricating ability, both regarding the stability of the oil and the revolutions of moving parts to be lubricated per unit of the oil used, it will be found that the oil with the least number of degrees between the initial boiling point and the end boiling point will be the more valuable oil.

Second—It has been found that asphaltic and paraffine base oils are equal in lubricating value, if the viscosity and boiling range are the same, and if the asphaltic base oils can be properly treated to remove asphaltic particles so that their viscosity and boiling range is the same as the paraffine base lubricating oil, and the present method described can accomplish this result by efficient fractionation and the removal of the asphaltic particles.

The advantages of the process lie particularly in the fractionation and withdrawal in the liquid phase of a lubricating oil distillate from a bubble tower which is capable of limiting the fraction withdrawn within a very narrow boiling point range. Furthermore this process covers any lubricating oil distillate having a Saybolt viscosity at 100° F. of more than 50, and which may be fractionated in liquid phase from a tower and from which the contained wax may be extracted or removed by chilling and filtration.

It is to be understood that in accordance with this invention the liquid withdrawn from the fractionating column and cooled, may be returned, either directly or indirectly, to the zone or plate from which it was withdrawn.

A distinct advantage of my process is that some of the heat which, by customary methods of fractionation, dependent upon utilization of reflux liquid, is carried by the continuously increasing volume of vapors to the top of the column, is removed by withdrawing liquid from the column, cooling it and returning it either directly or indirectly to the zone or plate in the column from which it was withdrawn. As a result the vapors which ordinarily would be required to carry from the column the heat so removed, are no longer necessary and the quantity of reflux liquid introduced at the top of the column may be accordingly reduced an appropriate amount. Such reduction of volume of vapors within the column will permit the introduction of more

vapors to be fractionated into the column, with a consequent increase in the amount of vapors which may be fractionated in a particular column over a given period of time, or, in other words, an increase in the capacity of the column or in the rate of fractionation. By the pump 9 and the associated valve controlled lines of the liquid circulating system, the rate of withdrawal and return of liquid from and to the column is controllable, with resultant control of the rate of abstraction of heat from the column.

I claim as my invention:

1. In the art of fractional distillation of petroleum, the process which comprises passing vapors upwardly through a plurality of fractionating zones at different levels, passing reflux liquid downwardly in a continuous stream through said zones countercurrent to and in contact with said vapors, withdrawing liquid from one of said zones and cooling it, and returning liquid so cooled to a zone at least as high as the zone from which it was withdrawn.

2. In the art of fractional distillation of petroleum, the process which comprises passing vapors through a plurality of fractionating zones, passing reflux liquid in a continuous stream through said zones countercurrent to and in contact with said vapors, withdrawing liquid from one of said zones and cooling it, and returning liquid so cooled to the zone from which it was withdrawn.

3. In the art of fractional distillation of petroleum, the process which comprises passing vapors of the oil through a plurality of fractionating zones, passing reflux oil in a continuous stream through said zones countercurrent to and in contact with the vapors, circulating liquid oil from and back to one of said zones, and cooling the liquid oil while in circulation external to said zone.

4. In the art of fractional distillation of petroleum the process which comprises passing vapors of the oil upwardly through a plurality of fractionating zones at different levels, passing reflux oil downwardly in a continuous stream through said zones countercurrent to and in contact with the vapors, circulating liquid oil from one of said zones back to a zone at least as high as the zone from which it is withdrawn, and cooling the liquid oil while in circulation external to said zones.

5. In the art of fractional distillation of petroleum, the process which comprises passing vapors of the oil upwardly through a plurality of fractionating zones at different levels, passing reflux oil downwardly in a continuous stream through said zones countercurrent to and in contact with the vapors, circulating liquid oil from one of said zones back to a zone at least as high as the zone from which it is withdrawn, cooling the liquid oil while in circulation external to

said zones, and drawing off a portion of the oil withdrawn from said one of said zones.

6. A fractionating system for petroleum comprising a fractionating column, means therein for defining a plurality of fractionating chambers at different levels, means within said column for conducting reflux liquid in a continuous stream downwardly therethrough, means for passing vapors of the liquid to be fractionated upwardly through the column countercurrent to and in contact with the reflux liquid, cooling means external to said column, and connections for withdrawing liquid from one of said chambers to said cooling means and for returning it to a chamber at least as high as the chamber from which it is withdrawn.

7. A fractionating system for petroleum comprising a fractionating column, means therein for defining a plurality of fractionating chambers at different levels, means within said column for conducting reflux liquid in a continuous stream downwardly therethrough, means for passing vapors of the liquid to be fractionated upwardly through the column countercurrent to and in contact with the reflux liquid, cooling means external to said column, connections for withdrawing liquid from one of said chambers to said cooling means and for returning it to a chamber at least as high as the chamber from which it is withdrawn, and means for drawing off a portion of the liquid withdrawn from said one of said chambers.

8. A fractionating system for petroleum comprising means for vaporizing the liquid to be fractionated, a feed line delivering to said means, a fractionating column receiving vapors from said means, means within said column for conducting reflux liquid in a continuous stream therethrough, a plurality of fractionating chambers in said column at different levels therein, means for conducting vapors upwardly from one of said chambers to another, cooling means external to said column, connections for delivering liquid from said feed line as cooling medium to said cooling means and for returning it to said feed line, and means for circulating liquid from one of said chambers to said cooling means and back to a chamber at least as high as said one of said chambers.

9. A fractionating system for petroleum comprising a fractionating column, a plurality of fractionating chambers therein at different levels, means for delivering vapors into and upwardly through said column, means for passing reflux liquid in a continuous stream downwardly through said column countercurrent to and in contact with said vapors in the several chambers of said column, connections from a plurality of said chambers for withdrawing liquid therefrom,

cooling means in communication with said connections, connections with a plurality of said chambers for returning cooled liquid thereto, and a common connection from the discharge of said cooling means to said last named connections.

10. A continuous process for producing a lubricating oil distillate having a narrow boiling point range and from which wax is removable, which comprises passing the vapors through a series of fractionating zones one above another, passing reflux liquid in a continuous stream from zone to zone countercurrent to and in contact with said vapors, withdrawing liquid from a zone intermediate the uppermost and lowermost of said zones, cooling the liquid so withdrawn, and returning cooled liquid to the zone from which it was withdrawn.
20. A continuous process for producing a lubricating oil distillate having a narrow boiling point range, and from which wax is removable, which comprises passing the vapors through a series of fractionating zones one above another, passing reflux liquid in a continuous stream from zone to zone countercurrent to and in contact with said vapors, withdrawing liquid from a zone intermediate the uppermost and lowermost of said zones, cooling the liquid so withdrawn, returning cooled liquid to a zone above that from which it was withdrawn, and again bringing the liquid so returned into contact with the vapors passing through said zones.
